UNITED STATES PATENT OFFICE.

ADOLF G. STAPEL, OF MONTGOMERY, ALABAMA.

SECTIONAL HOT-AIR FURNACE.

1,094,686.

Specification of Letters Patent. Patented Apr. 28, 1914.

Application filed June 8, 1911. Serial No. 631,964.

To all whom it may concern:

Be it known that I, ADOLF G. STAPEL, a citizen of the United States, residing at Montgomery, in the county of Montgomery and State of Alabama, have invented a new and useful Sectional Hot-Air Furnace, of which the following is a specification.

The present invention relates to improvements in sectional hot air furnaces, one object of the invention being the provision of a furnace, which is composed of a plurality of similarly shaped sections detachably connected together, whereby the longitudinal area of the furnace may be increased or decreased, proportionately to the grate surface.

A further object of the invention is the provision of a hot air furnace, composed of a plurality of sections detachably connected together, each of said sections comprising its respective part of the fire box, ash pit and radiating flues and main flue, so that when the sections are properly positioned in the outer shell, a maximum heating surface is presented to the air within the shell so that an exceedingly efficient furnace is the result.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a perspective view of a complete furnace embodying the present invention, a greater portion of the outer shell thereof being removed to show the exterior detailed construction of the sections. Fig. 2 is a sectional view of one of the sections *per se*. Fig. 3 is a longitudinal section through three sections and the front and rear plates of the furnace. Fig. 4 is a view in elevation of the front plate of the forward section. Fig. 5 is a similar view of the rear plate of the rear section. Fig. 6 is a detail sectional view of one of the side walls of the upper portion of a section. Fig. 7 is a cross section through a portion of the ash pit member of one of the sections. Fig. 8 is a side elevation of the same.

Referring to the drawings, the numeral 1 designates the base or any proper support

for the furnace, which has upstanding therefrom, the front frame 2 and the rear frame 3 which supports the casing or shell B, the frame 2 being provided with the sheet metal plate 4 while the frame 3 carries a sheet metal plate 5. The shell B, and sheet metal plates 4 and 5 constitute the outer casing of the furnace and incase the fuel container and heat radiating members, as will presently appear. The sheet metal plate 4 is provided with the draft and clean-out door 6 and with the fuel inlet door 7, there being provided a door 8 which constitutes the clean-out door for the hot air blast tube, as will presently appear. A clean-out tube 9 in communication with the smoke flue B' is provided.

The fuel combustion and heat radiating members of this furnace, are disposed as shown in Figs. 1 and 3, the cast-metal end plate A, shown in Fig. 4, being the sealing member for the first member of the furnace, as clearly shown in Figs. 1 and 3 and provided with the fuel receiving opening 23, the air blast tube opening 24 and the clean-out opening 25, which as shown in Fig. 3, is closed. The cast metal rear plate A', as clearly shown in Fig. 5 seals the rear end member or section of the furnace, as clearly shown in Fig. 3, and is provided with the flue opening 26. The lower section 22 is disposed at the lower end of the plate A, as clearly shown in Fig. 3, and is provided with an aperture adjacent the ash pit of the furnace, while the plate 22' of the rear plate A' seals the rear end of the ash pit.

Each one of the intermediate sections of the heating portion of the furnace, includes a lower ash pit member 12, having the connecting flanges 12'', and the longitudinally disposed shouldered rims 12' for the reception of the lower depending vertical walls 16 of the upper portion of the section. The walls 16, as clearly shown in Figs. 2 and 6, are inclined from the point 16' upwardly to the entrance to the flue B', there being a plurality, preferably three, of outstanding flanges 16'' formed integral with the inclined portion of the wall, the wall between the flanges being provided with the two openings 17' and 17'', which constitute the inlet and outlet for the products of combustion as clearly indicated by the arrows in Fig. 2. As shown there are six radiators 17 to each section, there being three at each side. Each radiator 17 is

adapted to surround its respective flange 16'', the upper and lower tie rods 18 being connected to the respective upper and lower outer edges of each radiator 17 and to the 5 outstanding flanges 16^a and 18' respectively. Each radiator 17 is a hollow cast metal member with the inner end open and slightly flared so as to neatly fit upon its respective flange 16'' and thus provide a 10 chamber having the inlet 17' and the outlet 17^a.

Carried by each member or section of the furnace and disposed to extend inclinedly downwardly into each radiator 17, 15 as clearly shown in Fig. 2, is a deflector or diaphragm 19, the upper end of which rests upon the solid portion of the inclined wall at a point adjacent to the lower edge of the upper outlet opening 17^a and to the adjacent 20 portion of the flange 16''. This deflector or diaphragm 19 may be secured in place in any desired manner or may be cast integral with the radiator 17, or the wall of the section.

25 A fire box lining 14 is disposed adjacent the walls 16 of each section of the furnace and forms with the grate 13, the fire box or fuel receptacle which is filled through the door 7 and opening 23 of the forward end 30 of the casing in the front wall A of the furnace. The bar 15 is connected to the bars of the grate 13 so that the bars of the grate may be operated.

An inwardly projecting ledge b is formed 35 adjacent the lower edge of each outlet opening 17^a, as clearly illustrated in Figs. 2 and 6, for the reception of the top 21 of the air blast tube of the furnace, the perforated plate 21' forming the bottom of the 40 flue and providing a means whereby air admitted at either end of the tube which is adjacent the opening 24 of the front plate A, will be deflected downwardly through the perforations of the plate 21' into the 45 dome of the combustion chamber formed of the sections above the inlet openings 17' thereof.

The supply of air to the ash pit and to 50 the hot air blast tube may be regulated in any desired manner. By positioning the blast tube, as shown, it is evident that air admitted therein and projected at the top or dome of the combustion chamber, thus 55 greatly assists in the complete combustion of the coal or soot, especially when the furnace is used to burn soft coal. It might be said that the air blast tube is only operated when soft coal is being burned, the door 8 at that time being left open, the same when 60 hard coal is used being closed, as shown in Fig. 1.

The lower inclined walls b' of the smoke flue B' are so formed, that any collection of soot within the flue will be directed downwardly upon the upper surface of the tri-

angular top 21 of the air blast tube and finally upon the deflectors 19, whose angle is such as to direct the soot downwardly into the inrushing products of combustion where the same will be burned, any residue therefrom falling upon the inclined lower wall of its respective radiator 17, and there directed through the openings 17' into the fire box of the furnace.

What is claimed is:

1. In a sectional furnace, the combination of an ash pit, a fire box and combustion chamber, a series of laterally extending chambers in communication with the combustion chamber, a diaphragm disposed outwardly and downwardly from the top of the combustion chamber into each laterally extending chamber, said diaphragm forming within each laterally extending chamber, a circuitous route for the products of combustion passing from the combustion chamber, and a flue into which all of said laterally extending chambers empty. 70 75 80 85

2. In a sectional furnace, the combination of an ash pit, a fire box, a combustion chamber having a domed central portion, a hot air blast tube entering said combustion chamber from the dome thereof, a flue, a series of laterally extending chambers forming a communication between the combustion chamber and the flue, and a division wall within each laterally extending chamber providing a deflecting means to deflect the products of combustion downwardly and outwardly before entering the flue. 90 95 100

3. In a sectional furnace, the combination of an ash pit, a fire box, a combustion chamber having a dome portion, a hot air blast tube entering into said dome portion at the apex thereof, a flue, chambers forming communication with the combustion chamber and the flue and extending laterally from the combustion chamber, and a deflecting diaphragm extending outwardly and downwardly within each lateral chamber. 105 110 115

4. In a furnace, the combination of an ash pit, a fire box, a combustion chamber provided with a reduced dome, a hot air blast tube located in the dome thereof and in communication with the top of the combustion chamber, a flue, a series of laterally extending and upwardly inclined chambers, there being an equal number upon each side of and in communication with the combustion chamber, and a diaphragm extending downwardly and outwardly from the top of the combustion chamber into each lateral chamber, and terminating at a point below the center line of its respective laterally extending chamber above the bottom and out of contact with the outer wall thereof. 120 125

5. In a furnace, a series of sections, each one of said sections being provided with its portion of a fire box, a combustion chamber, two oppositely disposed and laterally ex- 130 135

tending chambers in communication with the combustion chamber, a flue in communication with both of said laterally extending chambers, and a partition in each 5 of said laterally extending chambers extending from the top of the combustion chamber outwardly to provide two oppositely extending wings to cause the products of combustion to circulate through substantially the full area of the respective laterally extending chambers when passing from the combustion chamber to the flue.

6. In a furnace, the combination of a series 15 of sections, each section carrying its portion of an ash pit, a fire box, a combustion chamber, a pair of oppositely disposed and laterally extending chambers in communication at their lower ends with the combustion chamber, a flue common to both of the laterally extending chambers and in communication 20 therewith at their upper ends, and a diaphragm mounted in each laterally extending chamber to provide a circuitous route for the products of combustion passing from opposite sides of the combustion 25 chamber to opposite sides of the flue.

7. In a sectional furnace, the combination 30 of an ash pit, a fire box, a combustion chamber provided with a reduced dome, a lateral chamber upon each side of the combustion chamber and in communication at its lower end therewith, a diaphragm mounted in each lateral chamber, the upper portion of the wall of the combustion chamber providing a 35 lower inlet and an upper outlet in each of said lateral chambers, and a flue in communication with the upper ends of each lateral chamber.

8. A section of a hot air furnace, having a 40 portion of an ash pit, fire box, and combustion chamber, a pair of laterally extending and inclined chambers in communication with the combustion chamber at the bottom thereof and disposed to have the 45 respective outer and lower walls thereof inclined, a diaphragm disposed upon the upper end of the combustion chamber and extending downwardly and toward the lower portion of each of the respective laterally extending chambers and terminating at a point 50 to provide a passage-way around the lower end thereof and the bottom of its respective laterally extending chamber, and a flue common to all of said sections.

55 9. A section for a hot air furnace, having an ash pit, a fire box, a combustion chamber provided with a dome, a hot air blast tube in communication with the dome thereof and projecting upwardly, a flue directly above 60 said hot air blast tube, the lower walls of the flue being inclined toward the combustion chamber, a series of laterally extending chambers in communication with the combustion chamber and flue, and a deflector 65 disposed downwardly and outwardly from

the blast tube into each laterally extending chamber and dividing each of said chambers into two communicating compartments.

10. A section for a sectional furnace, comprising a main member providing a combustion chamber and a flue in direct communication, a hot air blast tube crowning the combustion chamber, said main member being provided with openings above and below said hot air blast tube, and laterally 70 extending chambers forming communication between the combustion chamber and flue.

11. A section for a sectional hot air furnace, comprising a main member providing the fire box, combustion chamber and flue, 80 said main member being provided with a series of apertures in its side walls, a series of laterally extending chambers connected to said member and over said apertures thereof to form communication with the 85 combustion chamber and flue through said apertures and the laterally extending chambers, and inclinedly disposed diaphragms, one to each of said lateral chambers dividing its respective chamber into two communicating 90 compartments through which the products of combustion pass before entering the flue.

12. In a sectional furnace, the combination of an ash pit, a fire box, a combustion 95 chamber provided with lateral openings therefrom and with a central opening in the apex thereof, a hot air blast tube closing the opening in the apex and in communication with the upper portion of the 100 combustion chamber, a series of laterally projecting chambers having their lower ends in communication with the combustion chamber, and downwardly inclined plates connected to the top of the combustion 105 chamber and extending into the lateral chambers and providing a space between their ends and the outer walls of the lateral chambers, and a flue in communication with the upper end of said laterally projecting 110 chambers.

13. In a hot air sectional furnace, the combination of an ash pit, a fire box, a sectional grate therein, a combustion chamber, said combustion chamber being provided with 115 a dome having openings at its lower edge and with a central longitudinal opening therein, a hot air blast tube bridging said central longitudinal opening and in communication with the dome of the combustion chamber, a flue, a series of laterally extending radiator chambers in communication with the lower openings of the combustion chamber and on each side thereof, and having their upper ends in communication 120 with the flue, and plates extending into each of said laterally extending chambers and below the top of the opening from the combustion chamber therein, to cause the products of combustion to be deflected 125 130

downwardly from the dome of the combustion chamber and be caused to pass through the laterally extending chambers before entering the flue.

14. In a furnace, the combination of an ash pit, a fire box, a combustion chamber having a tapered closed upper end, and having laterally extending openings in its sides near the fire box, a series of laterally extending radiator chambers in communication with the combustion chamber, inclined plates mounted therein with their lower ends extending below the top of the openings into said chambers, said inclined plates, each being of such a length as to divide the respective chambers into two communicating compartments, whereby the products of combustion are led from the combustion chamber throughout substantially the entire area of each respective laterally extending chamber, and a flue common to the upper ends of all of said laterally extending chambers.

15. In a furnace, the combination of an

ash pit, a fire box, a combustion chamber having a tapered dome, a flue directly above said dome provided with inclined walls leading from the dome of said combustion chamber, and oppositely extending radiator chambers in communication at their lower ends with the combustion chamber and in communication with the flue at their upper ends, and a diaphragm mounted in each of said laterally extending chambers and disposed to deflect the products of combustion from the combustion chamber downwardly into the lower portions of the respective laterally extending chambers to provide a circuitous route therefor from the combustion chamber to the flue.

In testimony that I claim the foregoing as my own, I have hereto affixed my signature in the presence of two witnesses.

ADOLF G. STAPEL.
